UNITED STATES PATENT OFFICE.

ARTHUR C. WITMAN, OF COLUMBUS, OHIO, ASSIGNOR TO GEORGE A. ROBBINS, OF COLUMBUS, OHIO.

DESIGN FOR A GAS-HEATER CASING.

Application filed August 4, 1922. Serial No. 3,293. Term of patent 14 years.

To all whom it may concern:

Be it known that I, ARTHUR C. WITMAN, a citizen of the United States, residing at Columbus, in the county of Franklin and State of Ohio, have invented a new, original, and ornamental Design for a Gas-Heater Casing, of which the following is a specification, reference being had to the accompanying drawing, forming part thereof.

Figure 1 is a front elevation of a gas heater casing, showing my new design, and Figure 2 is a side elevation of the same.

I claim:

The ornamental design for a gas heater casing, as shown.

ARTHUR C. WITMAN.
